(57) **CLAIM**

The ornamental design for a detachable pen for detecting markers in biological fluids, as shown and described.

DESCRIPTION

FIG. 1 is front view of a detachable pen for detecting markers in biological fluids according to our new design; FIG. 2 is a rear view thereof; FIG. 3 is a left side view thereof; FIG. 4 is a right side view thereof; FIG. 5 is a top view thereof; FIG. 6 is a bottom view thereof; FIG. 7 is a perspective view thereof; FIG. 8 is another perspective view thereof; and, FIG. 9 is an exploded perspective view of the detachable pen for detecting markers in biological fluids.
